LOCOMOTIVE PANTOGRAPH

Moses Zion, Brooklyn, N.Y., assignor to The Lionel Corporation, New York, N.Y., a corporation of New York

Filed Aug. 15, 1957, Ser. No. 678,375
3 Claims. (Cl. 46—217)

This invention relates to model railway trains and more particularly to model railway locomotives.

It is an object of the present invention to provide a pantograph assembly for model railway locomotives having means for effecting automatic adjustments in height so as to authentically simulate full scale electric locomotives.

It is a further object of the present invention to provide a pantograph assembly of the above type which may be readily mounted upon substantially any model railway locomotive, has a relatively few number of moving parts, and which is simply and authentically styled.

Other objects of the invention are to provide a pantograph for model railway locomotives bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

FIG. 1 is a perspective view of a model railway locomotive embodying pantographs made in accordance with the present invention;

FIG. 2 is a side elevational view of one of the pantographs shown in FIG. 1;

FIG. 3 is a side elevational view of the pantograph shown in FIG. 2;

FIG. 4 is an exploded side elevational view of the elements of the pantograph assembly;

FIG. 5 is an enlarged fragmentary cross sectional view showing the connection between certain parts of the device; and

FIG. 6 is an enlarged transverse cross sectional view taken along line 6—6 of FIG. 2.

In accordance with the present invention, a pantograph assembly has been provided that includes an upper and lower frame pivotally connected together and having a spring acting between certain parts thereof for effecting the vertical height adjustment, which pantograph may be readily applied to provide an authentic appearance to model electric railway locomotives.

Referring now more in detail to the drawing, a pantograph assembly 10 made in accordance with the present invention is shown in operative association, in FIG. 1, upon the top of a model railway locomotive 12. As is more clearly shown in FIG. 4, the pantograph 10 includes a lower base frame having a central portion 14 with spaced parallel and downwardly extending tabs 15 which provide means for securing the pantograph to the top of the locomotive. The upper surface of the central portion 14 is provided with a lug 17 at each corner, each such lug 17 having an outwardly and upwardly inclined surface 18. A bottom side arm 22 is pivotally connected to each end of the central portion 14 by means of yieldable flexible strips 25 which extend therebetween. The adjacent corners of the side arms 22 are provided with similar lugs 20 having upwardly and inwardly inclined surfaces 19 for engagement with the inclined surfaces 18 of the central portion lugs 17. As is more clearly shown in FIGURES 2 and 5 of the drawing, the lugs 17, 20 act as stops for limiting the upward pivotal movement of the side arms 22 relative

2

to the central portion 14 of the bottom frame about the pivotal connection formed by the flexible strips 25.

Referring now to FIGURE 3 of the drawing, it will be noted that each side arm 22 of the bottom frame 5 includes a pair of diagonally extending cross bars 27 which extend from one corner to the diagonally opposite corner thereof. The outer free end of each side arm 22 is also provided with a socket 29 through which a transverse bore 31 extends. Each of these bores 31 10 pivotally receives a pivot pin 33 integral with the outer free corner of each top side arm 34 of the upper frame which is also provided with cross bars 35. The central portion 37 of the top frame is provided with upwardly faceted simulated collector shoes 37 which are adapted to 15 contact a simulated overhead trolley wire. Similar flexible yieldable strips 38 pivotally connect each of the upper side arms 34 to the central portion of the upper frame, in a manner described in connection with the flexible strips 25 of the lower frame.

With the upper and lower frames assembled, as shown in FIG. 2, a tension spring 40 secured at opposite ends upon the junctures of each pair of cross bars 27 on the opposite side arms of the lower frame urges the outer ends of the frames toward each other, thereby raising 25 the collector shoes 37 upwardly relative to the fixed central portion 14 of the lower frame. This accurately simulates conventional pantographs and maintains the collector shoes 37 in contact with the trolley wire at all times. It will now be recognized that the respective 30 stops 17, 20 limit this upward movement of the collector shoes and prevents the complete collapse of the pantograph when the locomotive is removed from association with the overhead trolley wire. As a result, the true shape of the pantograph is maintained at all times, while providing sufficient resiliency to simulate actual pantograph movements.

While various changes may be made in the detail construction, it shall be understood that such changes shall be within the spirit and scope of the present invention as defined by the appended claims.

What I claim as new and desire to protect by Letters Patent of the United States is:

1. A toy pantograph for model railway locomotives 45 including parts of a size adapted to be mounted on such model railway locomotives, comprising a base frame having an upwardly extending lug at each end with an outer lower substantially vertical face and an upper beveled face, a bottom side arm on each side of said base frame each having a lug on the end adjacent said base frame with a substantially vertical lower face opposing the vertical face of the lug on said base member and with a beveled upper face at the same elevation 50 as the beveled upper face of the lug on said base member, flexible means connecting the lugs of said base member with each of said side arms intermediate the height of the vertical portions of said lugs, said side arms being pivotal upwardly to move the beveled faces of opposing 55 lugs of said base member and said side arms into contact, simulated collector shoe means, a pair of upper side arms, one end of each of which is pivotally connected to each respective bottom side arm at the end thereof which is unconnected to said base frame member and the other end of which is pivotally connected to said collector shoe means, and a spring connected to said bottom side arms at a location on each above the tops of said lugs when said pantograph is in a raised operative position with the beveled faces of said lugs in contact, said spring biasing said lugs into contact when said pantograph is 60 in said upper operative position.

2. A toy pantograph according to claim 1, wherein said base frame includes downwardly extending fastening means for securing said pantograph to the top of a model locomotive.

3. A toy pantograph according to claim 1, further comprising cross bars extending between bottom side

4
arms and between upper side arms on opposite sides of said base frame.
